4-ALKYL-1-(CYCLIC IMIDOALKYL) PIPERIDINES
 Kurt J. Rorig, Glenview, Ill., assignor to G. D. Searle &
 Co., Chicago, Ill., a corporation of Delaware
 No Drawing. Filed May 18, 1961, Ser. No. 110,852 5
 8 Claims. (Cl. 260—294)

This invention relates to 4-alkyl-1-(cyclic imidoalkyl) piperidines and processes for the manufacture thereof. More particularly, this invention relates to chemical compounds of the formula

wherein the alkyl radical called for optimally (but not exclusively) contains fewer than 14 carbon atoms, the alkylene radical called for optimally (but not exclusively) contains fewer than 3 carbon atoms, and R represents the hydrocarbon residue of a cyclic imide.

Illustrative of alkyl radicals optimally adapted to the purposes of this invention are methyl, ethyl, propyl, isopropyl, butyl, sec-butyl, tert-butyl, pentyl, neopentyl, hexyl, heptyl, octyl, nonyl, decyl, undecyl, dodecyl, tridecyl, and isomeric straight- and branch-chain hydrocarbon groupings of the formula

wherein n represents a positive integer less than 14. Correspondingly preferred alkylene radicals are methylene and ethylene, which is to say groupings of the formula

wherein x represents 1 or 2. Alkyl and alkylene radicals, both straight- and branched-chain, of higher than optimal carbon content are also within the purview of the described invention, albeit not individually named nor incorporated in the examples hereafter by reason of the greater interest which naturally attaches to maximally select species.

The hydrocarbon residues represented by R are most desirably saturated, as for example those derived from succinimide, glutarimide, alkyl-substituted succinimides and glutarimides such as pyrotartramide and 4-ethyl-4-methylglutarimide, 1,2-cyclohexanedicarboximide, etc., or preponderantly saturated as in the circumstance of their derivation from 1,2 cyclohexenedicarboximides. It follows from the above that R commonly but not necessarily exclusively represents a 2- or 3-carbon alkylene radical optimally substituted by 1 or more alkyl radicals and/or forming part of a substantially non-aromatic carbocycle.

The compounds to which this invention relates are useful because of their valuable and unexpected pharmaceutical properties. Among other things, they are anorectic agents, as also antibiotics characterized by a potent and various inhibitory effect on the growth of fungi such as *Trichophyton mentagrophytes* and bacteria such as *B. subtilis* and *E. coli*. Moreover, the claimed compounds operate to reduce the heat, swelling, and redness associated with the inflammatory response to tissue injury. 65

Manufacture of the imidomethyl products hereof proceeds by heating an appropriate imide

2

and piperidine

alkyl

10 with formalin, R being defined as before. An inert solvent, such as ethanol, is ordinarily employed, the reaction time ranging from a few minutes to perhaps as much as 1 hour. Imidoalkyl products wherein the alkyl constituent is ethyl or a higher homolog are similarly 15 prepared from a corresponding ω -haloalkylimide

20 the formalin, however, being omitted from the reaction mixture and an equivalent amount of potassium carbonate being introduced as an acid-binding agent. The time of the latter reaction is of the order of 48 hours, a solvent of choice being butanone.

The following examples describe in detail compounds illustrative of the present invention and methods which have been devised for their manufacture. However, the invention is not to be construed as limited thereby, either in spirit or scope, since it will be apparent to those skilled in the art of organic synthesis that many modifications, both of materials and of methods, may be practiced without departing from the purpose and intent of this disclosure. Throughout the examples hereinafter set forth, temperatures are given in degrees centigrade, pressures in millimeters of mercury, and relative amounts of materials in parts by weight, except as otherwise noted.

Example 1

4-methyl-1-succinimidomethylpiperidine.—To a mixture of 20 parts of succinimide, 20 parts of 4-methylpiperidine, and 17 parts of 36% formalin is added 1 part of a concentrated aqueous solution of potassium carbonate. 45 The resultant mixture is heated at about 99° for approximately 45 minutes, following which it is filtered hot and the filtrate chilled to induce precipitation. The white waxy precipitate thrown down is separated by filtration, 50 dried in air, and then recrystallized from pentane, affording iridescent flakes of 4-methyl-1-succinimidomethylpiperidine melting at approximately 87.5–88.5°. The product has the formula

Example 2

70 *4 - methyl - 1 - (3 - methylsuccinimidomethyl)piperidine.*—Substitution of 24 parts of pyrotartramide for the succinimide called for in Example 1 affords, by the pro-

3

cedure there detailed, 4-methyl-1-(3-methylsuccinimidomethyl)piperidine, of the formula

Example 3

(A) *4-tert-butylpiperidine*.—A solution of 125 parts of 4-tert-butylpyridine in 1000 parts of aqueous 75% acetic acid is maintained with agitation in the presence of 4 parts of platinum oxide catalyst under approximately 34 atmospheres of hydrogen at about 55° until hydrogen uptake indicates that saturation of the pyridine ring is accomplished—representatively, after 12 hours. Catalyst is then filtered off, solvent distilled, and the residual oil partitioned between 500 parts of concentrated sodium hydroxide and 800 parts of ether. The ethereal phase is separated and dried over anhydrous potassium carbonate, whereupon solvent is evaporated and the residue distilled in vacuo. The distillate coming over at 70–75°/17 mm. is 4-tert-butylpiperidine which, being disposed to react with atmospheric carbon dioxide, is preserved under nitrogen.

(B) *4-tert-butyl-1-succinimidomethylpiperidine*.—To a solution of 11 parts of succinimide in 80 parts of absolute ethanol is added 14 parts of 4-tert-butylpiperidine and 18 parts of 36% formalin. The resultant mixture is heated at approximately 90° for 15 minutes, then filtered hot. The filtrate is chilled and let stand to permit precipitation. The colorless felt-like needles thrown down are filtered off and washed with a small amount of ice-cold ethanol. The material thus isolated is 4-tert-butyl-1-succinimidomethylpiperidine melting at approximately 136–137°. The product has the formula

Example 4

4-nonyl-1-succinimidomethylpiperidine.—Substitution of 17 parts of 4-nonylpiperidine for the 4-tert-butylpiperidine called for in Example 3B affords, by the procedure there detailed, long slender white needles of 4-nonyl-1-succinimidomethylpiperidine melting at approximately 80–81°. The product has the formula

4

Example 5

(A) *4-decylpyridine*.—To a suspension of 19 parts of sodamide in 700 parts of liquid ammonia is added, with agitation during 30 minutes, 45 parts of 4-methylpyridine. A solution of 100 parts of nonyl bromide in 100 parts of ether is then added with agitation during 1 hour. The resultant mixture is maintained with agitation for 4 hours, whereupon 300 parts of ether is introduced and the ammonia then allowed to evaporate overnight, agitation being continued throughout. The residue is decomposed by addition of 200 parts of water. The ether phase is separated, washed with water, and extracted with dilute hydrochloric acid. The extract is made basic with concentrated aqueous sodium hydroxide and extracted, in turn, with ether. Solvent is removed from the ether extract and the residue distilled in vacuo. The distillate coming over at 127–132°/0.5 mm. is the desired 4-decylpyridine.

(B) *4-decylpiperidine*.—To a solution of 76 parts of 4-decylpyridine in 800 parts of ethanol is added 8 parts of 5% ruthenium-on-carbon catalyst. The resultant mixture is maintained with agitation at about 120° under approximately 34 atmospheres of hydrogen until saturation of the pyridine ring is complete, representatively, after 5 hours. Catalyst is then filtered off and the solvent distilled, whereupon the residue is distilled in vacuo. The fraction boiling at 96–110°/0.2 mm. is the desired 4-decylpiperidine.

(C) *4-decyl-1-succinimidomethylpiperidine*.—To a solution of 45 parts of succinimide in 400 parts of absolute ethanol is added 90 parts of 4-decylpiperidine and 74 parts of 36% formalin. The resultant mixture is heated at approximately 90° for 15 minutes, following which it is filtered hot, chilled, and let stand to permit precipitation. The colorless matted felt-like needles thrown down are separated by filtration and washed with 75 parts of ice-cold ethanol. The product thus isolated is 4-decyl-1-succinimidomethylpiperidine melting at 71–75°. It has the formula

45

50

55

Example 6

(A) *4-undecylpyridine*.—Substitution of 107 parts of decyl bromide for the nonyl bromide called for in Example 5 affords, by the procedure there detailed, 4-undecylpyridine boiling at 127–132°/0.5 mm.

(B) *4-undecylpiperidine*.—Substitution of 76 parts of 4-undecylpyridine for the 4-decylpyridine called for in Example 5B affords, by the procedure there detailed, 4-undecylpiperidine boiling at 134–144°/0.6 mm. The product is a solid at room temperature, melting at approximately 30°.

(C) *4-undecyl-1-succinimidomethylpiperidine*.—Substitution of 95 parts of 4-undecylpiperidine for the 4-decylpiperidine called for in Example 5C affords, by the procedure there detailed, 4-undecyl-1-succinimidomethylpiperidine.

5

methylpiperidine melting at 83-85°. The product has the formula

Example 7

(A) *4-tridecylpyridine*.—Substitution of 120 parts of dodecyl bromide for the nonyl bromide called for in Example 5A affords, by the procedure there detailed, 4-tridecylpyridine boiling at 137-147/0.3 mm.

(B) *4-tridecylpiperidine*.—Substitution of 76 parts of 4-tridecylpyridine for the 4-decylpyridine called for in Example 5B affords, by the procedure there detailed, 4-tridecylpiperidine boiling in the range 130-140°/0.2 mm.

(C) *4-tridecyl-1-succinimidomethylpiperidine*.—Substitution of 107 parts of 4-tridecylpiperidine for the 4-decylpiperidine called for in 5C affords, by the procedure there detailed, 4-tridecyl-1-succinimidomethylpiperidine melting at 83-85°. The product has the formula

Example 8

4-decyl-1-glutarimidomethylpiperidine.—To a solution of 51 parts of glutarimide in 400 parts of absolute ethanol is added 90 parts of 4-decylpiperidine and 74 parts of 36% formalin. The resultant mixture is heated at approximately 90° for 15 minutes, whereupon it is filtered hot, chilled, and let stand to permit precipitation. The colorless matted needles thrown down are filtered off and washed with 50 parts of ice-cold ethanol. The product thus isolated is 4-decyl-1-glutarimidomethylpiperidine, melting at 68-73° and having the formula

Example 9

1-glutarimidomethyl-4-undecylpiperidine.—Substitution of 95 parts of 4-undecylpiperidine for the 4-decylpiperidine called for in Example 8 affords, by the procedure there detailed, 1-glutarimidomethyl-4-undecyl-

6

piperidine melting at 67-72°. The product has the formula

Example 10

1-glutarimidomethyl-4-tridecylpiperidine.—Substitution of 107 parts of 4-tridecylpiperidine for the 4-decylpiperidine called for in Example 8 affords, by the procedure there detailed, 1-glutarimidomethyl-4-tridecylpiperidine melting at 62-70°. The product has the formula

Example 11

(A) *N-(2-bromoethyl)glutarimide*.—To a solution of 23 parts of glutarimide in 160 parts of absolute ethanol is added a solution of 5 parts of sodium in 110 parts of absolute ethanol. Solvent is removed by distillation at reduced pressures, and to the solid residue is added 130 parts of 1,2-dibromoethane. The resultant mixture is heated at the boiling point under reflux for 17 hours, then cooled to room temperature and filtered. Excess dibromoethane is removed from the filtrate by vacuum distillation; and the residue, a viscous oil, is extracted with a mixture of heptanes boiling in the range 77-115°. Distillation of solvent from this extract leaves as the residue *N*-(2-bromoethyl)glutarimide.

(B) *4-butyl-1-(2-glutarimidoethyl)piperidine*.—To a solution of 7 parts of 4-butylpiperidine and 11 parts of *N*-(2-bromoethyl)glutarimide in 40 parts of butanone is added 3 parts of powdered anhydrous potassium carbonate. The resultant mixture is heated with agitation at the boiling point of the solvent under reflux for 48 hours, then freed of insoluble matter by filtration and stripped of solvent by distillation. The residue is taken up in 5% hydrochloric acid. The acid solution is washed with ether, then saturated with an excess of potassium carbonate. The material salted out is extracted with a mixture of chloroform and ether, from which extract solvent is removed by distillation, leaving, as the residue the desired 4-butyl-1-(2-glutarimidoethyl)piperidine. The product has the formula

70

75

Example 12

4-tert-butyl-1-(4-ethyl-4-methylglutarimido-methyl)piperidine.—To a solution of 17 parts of 4-ethyl-4-methylglutarimide in 80 parts of absolute ethanol is added 14 parts of 4-tert-butylpiperidine and 18 parts of 36% formalin. The resultant mixture is heated at approximately 90° for 20 minutes, whereupon 80 parts of water is introduced. Precipitation occurs on cooling and standing. The crystalline solid thrown down is isolated by filtration, washed with 50% aqueous ethanol, and dried in air. The material thus isolated is 4-tert-butyl-1-(4-ethyl-4-methylglutarimido-methyl)piperidine melting at 72-73.5°. The product has the formula

Example 13

1-(4-ethyl-4-methylglutarimido-methyl)-4-nonylpiperidine.—Substitution of 17 parts of 4-nonylpiperidine for the 4-tert-butylpiperidine called for in Example 12 affords, by the procedure there detailed, 1-(4-ethyl-4-methylglutarimido-methyl)-4-nonylpiperidine as small white flakes melting at about 45-46.5°. The product has the formula

Example 14

4-tert-butyl-1-(1,2-cyclohexanedicarboximidomethyl)piperidine.—Substitution of 16 parts of 1,2-cyclohexanedicarboximide for the succinimide called for in Example 3B affords, by the procedure there detailed, 4-tert-butyl-1-(1,2-cyclohexanedicarboximidomethyl)piperidine as thick white plates melting at approximately 100-101°. The product has the formula

Example 15

1-(1,2-cyclohexanedicarboximidomethyl)-4-nonylpiperidine.—To a solution of 28 parts of 1,2-cyclohexanedicarboximide in 160 parts of absolute ethanol is added 31 parts of 4-nonylpiperidine and 32 parts of 36% formalin. The resultant mixture is heated at approximately 90° for 10 minutes, whereupon sufficient water is introduced to induce turbidity. On cooling, crystalline 1-(1,2-cyclohexanedicarboximidomethyl)-4-nonylpiperidine is thrown down. The product is filtered off, washed off, washed with 25 parts of 50% ethanol, and dried in air. The white flakes thus obtained melt at 57-59°. The product has the formula

Example 16

1-(1,2-cyclohexanedicarboximidomethyl)-4-decylpiperidine.—To a solution of 69 parts of 1,2-cyclohexanedicarboximide in 400 parts of absolute ethanol is added 90 parts of 4-decylpiperidine and 74 parts of 36% formalin. The resultant mixture is heated at approximately 90° for 15 minutes, then filtered hot, chilled, and let stand to permit precipitation. The colorless solid thrown down is filtered off and washed with 50 parts of ice-cold ethanol. The 1-(1,2-cyclohexanedicarboximidomethyl)-4-decylpiperidine thus obtained melts at 60-64° and has the formula

Example 17

1-(1,2-cyclohexanedicarboximidomethyl)-4-undecylpiperidine.—Substitution of 95 parts of 4-undecylpiperidine for the 4-decylpiperidine called for in Example 16 affords, by the procedure there detailed, 1-(1,2-cyclohexanedicarboximidomethyl)-4-undecylpiperidine melting at 67-70°. The product has the formula

Example 18

1-(1,2-cyclohexanedicarboximidomethyl)-4-tridecylpiperidine.

peridine.—Substitution of 107 parts of 4-tridecylpiperidine for the 4-decylpiperidine called for in Example 16 affords, by the procedure there detailed, 1-(1,2-cyclohexanedicarboximidomethyl)-4-tridecylpiperidine melting at 68–71°. The product has the formula

Example 19

4-tert-butyl-1-(4-cyclohexene-1,2 - dicarboximidomethyl)piperidine.—To a solution of 16 parts of 4-cyclohexene-1,2-dicarboximide in 80 parts of absolute ethanol is added 14 parts of 4-tert-butylpiperidine and 18 parts of 36% formalin. The resultant mixture is heated at approximately 90° C. for 15 minutes, whereupon sufficient water is introduced to induce turbidity. Crystallization occurs on cooling and standing. The product thrown down is filtered, washed with 25 parts of aqueous 70% ethanol, and dried in air. The white powdery 4-tert-butyl-1-(4-cyclohexene-1,2 - dicarboximidomethyl)piperidine thus obtained melts at approximately 117-118° and has the formula

Example 20

1-(4-cyclohexene-1,2-dicarboximidomethyl) - 4-nonylpiperidine.—Substitution of 17 parts of 4-nonylpiperidine for the 4-tert-butylpiperidine called for in Example 19 affords, by the procedure there detailed, 1-(4-cyclohexene-1,2-dicarboximidomethyl)-4-nonylpiperidine in the form of a white powder melting at approximately 71–72°. The product has the formula

Example 21

1-(4-cyclohexene-1,2-dicarboximidomethyl)-4-decyl-piperidine.—To a solution of 68 parts of 4-cyclohexene-1,2-dicarboximide in 400 parts of absolute ethanol is 75

added 90 parts of 4-decylpiperidine and 74 parts of 36% formalin. The resultant mixture is heated at approximately 90° for 15 minutes, following which it is filtered hot, chilled, and allowed to cool and precipitate. The colorless solid thrown down is recovered on a filter and washed with 50 parts of ice-cold ethanol. This material is 1-(4-cyclohexene-1,2-dicarboximidomethyl)-4-decylpiperidine, melting at 69-74° and having the formula

Example 22

1-(4-cyclohexene-1,2 - dicarboximidomethyl)-4-undecylpiperidine.—Substitution of 95 parts of 4-undecylpiperidine for the 4-decylpiperidine called for in Example 21 affords, by the procedure there detailed, 1-(4-cyclohexene-1,2-dicarboximidomethyl)-4 - undecylpiperidine melting at 76-78°. The product has the formula

Example 23

45 1-(4-cyclohexene-1,2-dicarboximidomethyl)-4-tridecylpiperidine.—Substitution of 107 parts of 4-tridecylpiperidine for the 4-decylpiperidine called for in Example 21 affords, by the procedure there detailed, 1-(4-cyclohexene-1,2-dicarboximidomethyl)-4-tridecylpiperidine melting at 78-82°. The product has the formula

What is claimed is:

1. A compound of the formula

11

wherein the alkyl radical called for contains fewer than 14 carbon atoms.

2. 4-methyl-1-succinimidomethylpiperidine.
3. A compound of the formula

5

10

15

12

6. 1-(4-cyclohexene-1,2-dicarboximidomethyl)-4-nonylpiperidine.

7. A compound of the formula

wherein the alkyl radical called for contains fewer than 14 carbon atoms and x represents a positive integer less than 3.

4. 1-glutarimidomethyl-4-undecylpiperidine.
5. A compound of the formula

wherein the alkyl radical called for contains fewer than 14 carbon atoms.

20 wherein the alkyl radical called for contains fewer than 14 carbon atoms.

8. 4-tert-butyl-1-(4-ethyl-4-methylglutarimidomethyl)piperidine.
